Primary Examiner — Sandra Snapp*Assistant Examiner* — Ieisha N Price(74) *Attorney, Agent, or Firm* — Jenei LLC(57) **CLAIM**

The ornamental design for a knife, as shown and described.

DESCRIPTION

FIG. 1 is a bottom, left side perspective view of a knife;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1; and,

FIG. 8 is an enlarged view taken from indication circle 8 of FIG. 1.

The broken lines showing of the knife illustrates the environment of the claimed design and forms no part thereof. The dot-dot-dash broken lines rendered in FIGS. 1 and 8 form no part of the claimed design.

1 Claim, 7 Drawing Sheets(56)
